UNITED STATES PATENT OFFICE.

MARIUS MATHIESSEN, OF CHICAGO, ILLINOIS, ASSIGNOR TO MATHIESSEN-SANDBERG COMPANY, OF CHICAGO, ILLINOIS, A CORPORATION OF ILLINOIS.

COLLAPSIBLE LOOP AERIAL.

Application filed March 6, 1925. Serial No. 13,598.

My invention relates to improvements in portable aerials of the loop form and has particular reference to an improved construction by which the loop can be readily collapsed for transportation and as readily extended for use.

Such aerials usually comprise a mast and arms providing a frame upon which the aerial wire is wound in a plurality of turns. 10 A particular feature of my present invention relates to simple means whereby a two part mast can readily be arranged in rigid extended form, the parts of the mast carrying arms hingedly connected thereto so that they can be swung in against the parts of the mast for arranging the parts in a small compact arrangement for packing and shipment.

A further feature relates to a simple 20 means of connecting the two parts of the mast to securely retain them in end to end rigid extended condition and permit them to be readily arranged in substantially parallel relation and occupying a minimum of 25 space longitudinally.

Another feature relates to a novel manner of arranging the connecting wires whereby no loose ends are seen when the device is set up and connected.

30 A further feature relates to the provision of a hollow support for the loop down through which the connecting ends of the loop wire are carried, in combination with stop means for preventing the rotation of 35 the loop through more than one revolution in each direction.

Other advantages and features of importance will appear hereinafter.

40 My invention will be more readily understood by reference to the accompanying drawings forming part of this specification and in which:—

Figure 1, is a perspective view of a collapsible loop aerial embodying my invention in one form;

Figure 2, is an elevational view of the frame work shown folded into a compact form;

Figure 3, is a fragmentary, vertical, central, section on the line 3—3 of Figure 1;

Figure 4, is a fragmentary, vertical, section on the line 4—4 of Figure 1;

Figure 5, is a plan section on the line 5—5 of Figure 1;

50 Figure 6, is a fragmentary, elevational

view, showing a different manner of connecting the two parts of the mast; and

Figure 7, is a fragmentary, vertical, section on the line 7—7 of Figure 6.

In said drawings, 1 designates generally a 60 foldable or collapsible frame upon which an aerial wire 2 is adapted to be wound in a plurality of turns 3. The frame is adapted to be mounted in vertical position on a spindle 4, which may be rigidly mounted in vertical 65 position on a suitable base 5. The base 5 may represent a separate member or may represent a top panel or member of a suitable radio cabinet, but in either case the spindle 4 is hollow so that the ends 6 of the 70 wire 2 may be carried down through the spindle below the base for convenience in connecting them with suitable binding posts 7 on the base or with the apparatus in the cabinet, as may be.

75 The frame 1 consists of a mast 8 upon which are hinged a plurality of arms, preferably two pairs of arms 9 and 10, one above the other, and the ends of the arms and the top and bottom of the mast are provided with 80 cross pieces 11 for receiving the several turns 3 of the aerial wire. Preferably the turns 3 of the wire are secured in a spaced relation on the cross pieces 11 by suitable cap members 12.

85 The mast 8 consists of two sections, an upper section 13 and a lower section 14, and the lower section preferably has a tubular reinforcing part 15 at its lower end. The lower pair of arms 9 are hinged to the power part 14 far enough from its lower end to permit them to swing down and in against the lower part 14 of the mast, as shown in Figure 2.

90 The upper pair of arms 10 are hinged to a short piece of tubing 17 which is slidable up and down on the mast, and which part is limited in its downward movement by a stop pin 18 projecting from the mast. The arrangement is such that when the sliding arm support 17 is at the lower limit of its movement the arms 10 are extended horizontally, and when this support is moved up the mast the arms 10 are swung in against the upper part 13 of the mast, as shown in Figure 2.

95 The two parts 13 and 14 of the mast are preferably rigidly connected in extended condition by means of a tubular doweling member 19 arranged at their adjacent ends and preferably rigidly secured on the upper 100 105 110

end of the part 16 of the mast and projecting above same to provide a socket for receiving the lower end of the upper part 13 of the mast. The turns 3 of the loop wire 5 are tensioned when the frame is extended and this tensioning of the turns hold the two parts of the mast tightly together.

The tensioning of the wire is accomplished by winding the wire on the frame with the 10 upper pair of arms slightly collapsed, then when the support 17 is pushed down against the stop 18 the turns are tightly stretched. In collapsing the frame the upper pair of arms are first swung in by pushing the support 15 17 upwardly, then the upper part 13 of the mast can be lifted up out of the connecting socket and dropped down alongside the lower part 14 of the mast, as shown in Figure 2, at which time the lower pair of arms 20 are swung down and in against the lower part 14 of the mast.

As explained hereinbefore, the spindle 4 is hollow and the ends of the loop wire are carried down through the spindle. They are 25 thus out of sight and the device presents a very neat appearance. As the loop is rotatably mounted on the spindle for the purpose of permitting it to be readily set for attaining the best results and as the ends 6 of the 30 loop wire are out of sight, I provide simple means for preventing the rotation of the frame through more than one revolution, as otherwise the ends 6 might become damaged. This means consists of a stop pin 20 fixed to 35 the base 5 and a second stop pin 21 projecting out from the lower end of the mast and adapted to contact with the pin 20 as the mast is rotated in either direction.

Instead of the doweling together of the 40 two parts 13 and 14 of the mast I sometimes simply connect their adjacent ends together by a hinge 22, as shown in Figures 6 and 7, the upper part 13 being free to be swung down into parallel relation with the lower 45 part 14. In the forms shown herein the frame work is collapsible into a compact bundle which is but slightly longer than one-half the height of the extended mast.

As many modifications of my invention 50 will readily suggest themselves to one skilled in the art, I do not limit or confine my invention to the specific details of construction herein described.

I claim:

55 1. In a collapsible loop aerial, a mast made of two parts adapted to be arranged in end to end abutting relation when the loop is extended, means for retaining the parts rigidly in loop extended position, arms hingedly 60 mounted on the mast and adapted to be swung in parallel thereto when the loop is collapsed, the two parts of the mast adapted to be arranged substantially parallel to each other and in a compact relation when the 65 loop is collapsed.

2. In a collapsible loop aerial, a mast made of two parts adapted to be arranged in end to end abutting relation when the loop is extended, socket means for retaining the parts in loop extended position, arms hingedly 70 mounted on the mast and adapted to be swung in substantially parallel to the mast when the loop is collapsed, the two parts of the mast adapted to be moved endwise to arrange them parallel to each other and in a 75 compact relation when the loop is collapsed.

3. In a collapsible loop aerial, a mast made up of two separable parts adapted to be moved relatively endwise to extend or collapse the loop, a socket carried by one part 80 for receiving an end of the other part for retaining the parts in extended relation, hinged arms carried by each part, cross arms fixed at the ends of the mast and the arms, and an aerial wire wound in a plurality of 85 spaced turns on said cross arms.

4. In a collapsible loop aerial, a two part mast, the parts adapted to be arranged in end to end abutting relation when the loop is extended and in adjacent parallel relation 90 substantially throughout their entire length when the loop is collapsed, means carried by one part for receiving the other part for retaining the abutting ends against relative sidewise movement, a pair of arms hinged to one part, and a pair of arms hinged to a member slidably mounted on the other part, as and for the purpose described.

5. In a loop antenna, a mast, and upper and lower sets of wire loop supporting arms 100 pivoted on said mast for movement outwardly to extended position and inwardly to folded position along the mast, cross arms at the ends of the mast and arms, the outer ends of the arms being free of any frame 105 connections, one of said sets movable longitudinally of the mast toward and from the other set.

6. In a loop antenna, a mast, upper and lower wire loop supporting arms, disposed in substantially the same vertical plane, a wire 110 loop carried by and fixed on said arms, the upper arms movable inwardly to collapse the loop and outwardly to reform the same, the ends of the arms being free of connections 115 except the antenna wire, and a spring controlled device for securing the upper arms in extended outward position on the mast forced outwardly against the wire loop to tighten and place the same under tension.

7. In a loop antenna, a mast, independent sets of wire loop supporting arms mounted on said mast disposed in substantially the same vertical plane, the ends of the arms being free of other connections except the 125 antenna wire, and one of said sets of arms, movable longitudinally of the mast toward and from an adjacent set of said arms.

8. In a loop antenna, a mast, independent sets of wire loop supporting arms mounted 130

on said mast, a wire receiving member on the mast, a wire loop carried on and around said arms and member, the outer ends of the arms being free of connections other than 5 the antenna wire, one of said sets of arms movable longitudinally along the mast to and from position to collapse said wire loop.

9. In a loop antenna, a base, a mast rotatably supported by the base, outwardly extending wire loop supporting arms pivoted to the lower portion of the mast for swinging inwardly therealong, a collar mounted for reciprocation on the upper portion of the mast, a pair of outwardly extending arms 10 hinged to said reciprocating collar and normally disposed with their inner ends against said collar, said last mentioned arms being

adapted to move toward the mast axis, and toward each other, when said reciprocating collar is moved on the mast to cause relative 20 swinging movement between said reciprocating collar and its associated arms, horizontally disposed cross members carried by the arms at their outer extremities and by the mast, and a wire loop carried by said cross 25 members and held tautly in loop forming position when said arms are in their extended positions, the outer ends of the arms being free of connections other than the antenna wire. 30

In testimony whereof, I have hereunto set my hand, this 27th day of February, 1925.

MARIUS MATHIESEN.
